UNITED STATES PATENT OFFICE.

PATRICK J. HANLEY, OF ELIZABETH, NEW JERSEY.

SHUTTLE HOLDER AND DRIVER FOR SEWING-MACHINES.

No. 811,499.

Specification of Letters Patent.

Patented Jan. 30, 1906.

Application filed February 23, 1905. Serial No. 246,873.

To all whom it may concern:

Be it known that I, PATRICK J. HANLEY, a subject of the King of Great Britain, and a resident of Elizabeth, in the county of Union 5 and State of New Jersey, have invented a new and Improved Shuttle Holder and Driver for Sewing-Machines, of which the following is a full, clear, and exact description.

This invention relates to improvements in 10 sewing-machine shuttle holders and drivers of the type having an oscillating movement, the object being to provide a simple and novel means for holding the shuttle in position, doing away with the usual shuttle-race, and 15 thereby obviating the friction incident to a shuttle operating in a race of the ordinary construction.

Other objects of the invention will appear 20 in the general description.

20 I will describe a shuttle holder and driver embodying my invention and then point out the novel features in the appended claims.

Reference is to be had to the accompanying 25 drawings, forming a part of this specification, in which similar characters of reference indicate corresponding parts in all the figures.

Figure 1 is a face view of a shuttle holder 30 and driver embodying my invention. Fig. 2 is a section on the line *x x* of Fig. 1. Fig. 3 shows the holder in plan. Fig. 4 is a sectional view showing the bobbin-case retainer. Fig. 5 is an edge view of the shuttle. Fig. 6 35 shows a modified form of holder, and Fig. 7 is a plan thereof.

35 Referring to the drawings, 1 designates a shuttle-driver attached in the usual manner to a rock-shaft 2. The arms of the driver are provided on the outer side and at the opposite sides with lugs 3, which have tapped per- 40 forations for receiving pivot-screws 4, on which the holding devices 5 are mounted to swing.

In Figs. 1, 2, and 3 the holding devices 45 which engage at the opposite sides of the shuttle 6 are substantially in the form of rings, and extended outward from one side are finger-pieces 7, between which a spring 8 is ar- 50 ranged to hold the holding devices yieldingly against the shuttle. In said Figs. 1, 2 and 3 the holding rings or devices have a swinging movement in the direction of the axis of the shuttle. In Figs. 6 and 7, however, the holding 55 devices consist of arms 9, which receive the shuttle at its upper and lower edges, the upper and lower arms being doubled and spaced apart, so as to engage against the in-

ner and outer sides of the shuttle, and these arms 9 are held yieldingly in engagement with the shuttle by means of a spring 10, placed between the finger-pieces 11. A bob- 60 bin 12 is placed in the usual bobbin-case 13, which is mounted on a post 14, arranged in the bobbin. The bobbin-case is held in position by means of a latch-plate 15, here shown as having swinging connection with a retain- 65 ing-ring 16, depending from a front slide 17, on the bed-plate of the machine. The latch-plate 15 is held yieldingly against the bobbin-case by means of a spring 18, and the said bobbin-case is held from rotary movement by 70 means of a finger 19 thereon engaging in a notch 20, formed in the upper portion of the retaining-ring 16.

75 While I have described the latch 15 as attached to a retaining-ring, it is to be understood that it may be mounted on any other part of the machine. The shuttle 6 is provided in its edge with a circumferentially-disposed slot 21, through which the thread from the bobbin passes. This slot is quite long 80 and permits of oscillating movements of the shuttle without drawing the threads away from the needle-opening. The thread is inserted into the slot 21 through an outwardly-opening slot 22, formed in the shuttle. 85

To remove the shuttle, the slide-plate 17 is to be drawn outward, and then by pressing the finger-pieces 7 or 11 toward each other the holding-rings will be spread apart, and then the shuttle may be readily removed or 90 placed in position. Of course the bobbin-case may be removed without disturbing the shuttle or its holder.

Having thus described my invention, I claim as new and desire to secure by Letters 95 Patent—

1. A sewing-machine shuttle-holder comprising a driver, spring-pressed shuttle-holding devices on the driver, a bobbin-case removably placed in the shuttle, a finger on the 100 bobbin-case, and a stationary part having a notch to receive said finger.

2. A sewing-machine shuttle-holder comprising a shuttle-driver, holding devices having pivotal connection with said driver and 105 adapted for engaging with opposite sides of the shuttle, outwardly-extending finger-pieces on said holding devices, and a spring arranged between the finger-pieces.

3. A sewing-machine shuttle-holder comprising a shuttle-driver, spring-pressed holding devices mounted to swing on said driver 110

and adapted for engaging with opposite sides of the shuttle, a bobbin - case removably placed in the shuttle, a retaining-ring depending from a slide-plate of the sewing-machine, the said ring being provided with a notch, a finger on the bobbin-case for engaging in said notch, and a spring-pressed latch on the retaining-ring for engaging with the bobbin-case.

In testimony whereof I have signed my name to this specification in the presence of subscribing witnesses.

PATRICK J. HANLEY.
